(57) **CLAIM**

The ornamental design for a vacuum cleaner with base and attachments, as shown and described.

DESCRIPTION

FIG. 1 is a perspective view of a vacuum cleaner with base and attachments showing our new design;

FIG. 2 is a perspective view viewed from another angle thereof;

FIG. 3 is a front elevation view thereof;

FIG. 4 is a rear perspective view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines depict portions of the vacuum cleaner with base and attachments that form no part of the claimed design.

The vacuum cleaner with base and attachments is shown with a symbolic break in its length. The appearance of any portion of the vacuum cleaner with base and attachments between the break lines forms no part of the claimed design.
